Inventor:

Fletcher Sparling
by Crosby & Gregory attys.

UNITED STATES PATENT OFFICE.

FLETCHER SPARLING, OF BOSTON, MASSACHUSETTS.

SWITCH-ACTUATOR FOR STREET-CARS.

SPECIFICATION forming part of Letters Patent No. 518,972, dated May 1, 1894.

Application filed June 17, 1893. Serial No. 477,920. (No model.)

To all whom it may concern:

Be it known that I, FLETCHER SPARLING, of Boston, county of Suffolk, State of Massachusetts, have invented an Improvement in 5 Switch-Actuators for Street-Cars, of which the following description, in connection with the accompanying drawings, is a specification, like letters on the drawings representing like parts.

10 This invention has for its object the production of a switch actuator for use on street railway cars, whereby the switch point may be readily turned by the driver or motorman without leaving his post, the actuator being 15 held normally in inoperative position.

In accordance therewith my invention consists, in a switch actuator for street cars, of a yielding support connected to the car, and normally elevated, combined with an actuator 20 connected to said support and adapted to be swung laterally and provided with an operating handle, and independent means to positively depress the support and actuator, substantially as will be described.

25 Other features of my invention will be hereinafter described and particularly pointed out in the claims.

Figure 1, in side elevation, represents the end of a car with my invention applied there- 30 to, and Fig. 2 is a partially sectional view taken below the line x, Fig. 1.

The platform a, and dasher a' are and may be of usual construction in either horse or electric street cars.

35 I have herein shown depending ears b secured to the under side of the car by a suitable bolt b', see dotted lines Fig. 1, said ears sustaining the rear end of a support c for the actuator, said support being shown as slotted

40 at c' to loosely surround and be guided by a depending bolt or pin d rigidly secured to the under side of the platform a, and encircled by a spiral spring d^x between the support c and a nut d' on the lower end of the stud, the latter preferably being threaded in order that the tension of the spring may be adjusted.

45 The actuator support c is normally maintained in the position shown in Fig. 1 by the spring d^x, and it is obvious that any other 50 convenient form of spring might be used for the same purpose. The outer end of the support c is bifurcated or forked at c², and as

shown herein projects a short distance beyond the platform a. A pin or stud e is pivotally held in the bifurcated portion by a 55 rock-shaft e' at right angles thereto.

I have herein shown the switch actuator as a lever f pivoted upon the pin or stud e, the upper end of the lever extending above the dasher a' and having a handle f' within reach 60 of the driver. The lower end of the lever is offset at f², see Fig. 2, and slightly curved at f³. A push pin g is extended loosely through the platform, its lower end bearing against the support c, so that depression of said pin 65 forces the outer end of the support down against the spring d^x and moves the end f³ of the actuator into position to engage the switch point. Movement of the handle f' to the right or left moves the switch point to 70 left or right according to the direction which the car is to take. When the point has been properly moved the pin g is released and the spring d^x immediately raises the support c and the actuator into normal inoperative position. The pin or stud e and the rock shaft 75 e' to which it is secured form a universal joint between the actuator and its support, whereby the former can be moved to the right or left, forward or back, as desired. As the 80 end f³ is offset it can be readily seen by the driver or motorman, and its movement readily directed to properly actuate the switch point.

If a fender is attached to the car it will not 85 interfere with the operation of the switch actuator, for the fender can be slotted to admit the actuator therethrough.

A guard g' of usual construction may be employed, if desired, to prevent the actuator 90 from moving on its pivot when not in use.

I claim—

1. In a switch actuator for street cars, a yielding support connected to the car, and normally elevated, combined with an actuator 95 connected to said support and adapted to be swung laterally and provided with an operating handle, and independent means to positively depress the support and the actuator, substantially as described.

2. In a switch actuator for street cars, a bifurcated support pivoted to the car, a spring to normally maintain said support in elevated position, combined with an actuator jointed

to the bifurcated portion of said support, means to positively depress the support and actuator, and a handle to turn the actuator and throw the switch point, substantially as described.

3. A switch actuator for street cars, consisting of a yielding support, an actuator carried thereby, and a universal joint connecting them, combined with means to move the

actuator into operative position, substantially as described.

In testimony whereof I have signed my name to this specification in the presence of two subscribing witnesses.

FLETCHER SPARLING.
